(57) **CLAIM**

The ornamental design for a step assembly with solar operated lights, as shown and described.

DESCRIPTION

FIG. 1 is a front perspective view of the step assembly with solar operated lights showing my design;

FIG. 2 is an enlarged fragmentary view of the encircled portion labeled as "2" in FIG. 1;

FIG. 3 is a right side elevational view thereof;

FIG. 4 is a left side elevational view thereof;

FIG. 5 a top plan view thereof;

FIG. 6 is a cross-sectional view thereof, taken along line 6-6 in FIG. 5;

FIG. 7 is a cross-sectional view thereof, taken along line 7-7 in FIG. 5;

FIG. 8 is a bottom plan view thereof;

FIG. 9 is a front elevational view thereof;

FIG. 10 is a rear elevation view thereof;

FIG. 11 is a cross-sectional view thereof, taken along line 11-11 in FIG. 9;

FIG. 12 is a cross-sectional view thereof, taken along line 12-12 in FIG. 9;

FIG. 13 is a cross-sectional view thereof, taken along line 13-13 in FIG. 10; and,

FIG. 14 is a cross-sectional view thereof, taken along line 14-14 in FIG. 10.

The long dash short dash lines in FIGS. 1-2 depict the boundary of the enlarged fragmentary view area and form no part of the claimed design. The dash broken lines shown in FIG. 8 illustrate portions of the step assembly with solar operated lights that form no part of the claimed design.
